UNITED STATES PATENT OFFICE.

EDWIN F. NEWELL, OF MIDDLETON, CONNECTICUT.

BLIND-SLAT JOURNAL.

SPECIFICATION forming part of Letters Patent No. 552,541, dated January 7, 1896.

Application filed August 5, 1895. Serial No. 558,235. (No model.)

To all whom it may concern:

Be it known that I, EDWIN F. NEWELL, a citizen of the United States, residing at Middletown, in the county of Middlesex and State 5 of Connecticut, have invented certain new and useful Improvements in Blind-Slat Journals, of which the following is a specification.

This invention relates to an attachment for a blind or shutter slat, and the object of the 10 invention is to provide a repair-journal in the nature of a sheet-metal tenon or attachment that can be quickly and easily attached to a slat when in the manipulation of the blind or slat the ordinary wooden tenon has been 15 broken or worn off and without the removal of the slat from the blind or shutter.

A further object of the invention is to provide an attachment that is simple and durable in construction and can be readily stamped 20 out of sheet metal in the nature of flat wire at one operation and at a minimum cost.

In the drawings accompanying and forming part of this specification, Figure 1 represents a portion of the shutter or blind having 25 slats secured in position thereon by means of this improved attachment, a portion of the shutter being shown in section to more clearly illustrate this improved attachment. Fig. 2 is a partially sectional view taken in line *a a*, 30 Fig. 1, looking toward the right hand thereof. Fig. 3 is a cross-sectional view of one of the side frames of a shutter having a slat in position thereon and showing a longitudinal sectional view of the attachment. Fig. 4 is an 35 end view of the tenon detached; and Fig. 5 is a longitudinal sectional view of the tenon, also detached. Fig. 6 is a side elevation of a tenon provided with bent ends or projections.

Similar characters represent like parts in 40 all the figures of the drawings.

This improved attachment or tenon comprises a suitable device adapted for attachment to a blind or shutter slat when the ordinary wooden tenon formed on the slat has in 45 the manipulation of the blind or slat been broken off and which device can be quickly and easily attached to a slat without the removal of the same from the shutter or blind.

In movable slats of shutters or blinds as 50 ordinarily constructed the ordinary wooden tenons forming the journals on which the slats oscillate frequently break off, whereby the

slats become inoperative, and with two or three such slats in a shutter such shutter becomes worthless and an unsightly object, and 55 as these wooden tenons are formed on the slats there is no means of remedying this defect without replacing the broken slat by an entirely new slat, which necessarily requires the shutter to be taken apart to insert the slat. 60

In order to remedy the above defect I have devised an attachment more especially adapted for the use of painters and other artisans who desire to repair broken shutters or blinds while at work upon a house and which can be 65 quickly and easily attached without taking the shutter or blind apart or without even taking the shutter from its hinges. This improved slat attachment, in the preferred form thereof herein shown and described, comprises a metal tenon, preferably composed of flat wire, (designated in a general way by A and consisting of a substantially cylindrical journal 10,) having elongated laterally-extending flanges 11, provided with apertures 70 12 for the reception of nails or screws for attaching the tenon to the end of a blind-slat.

These flanges may, if desired, be provided at their outer ends with bent projections 17, which can be inserted into the blind-slat to 80 hold the same thereon while the nails are being hammered into the slat and which would also serve as a reinforcing attaching means to hold the device onto the slat.

The journal 10 of the tenon is preferably 85 U-shaped in cross-section and is provided with inwardly-turned sides or flaps 14, whereby the journal forms a substantially cylindrical bearing-surface for the journal-bearing 90 15 in the side frames of the shutter.

The entire device may be quickly and easily stamped out of sheet metal in the nature of flat wire in the preferred form thereof at one operation and placed on the market for sale at a nominal cost. 95

In the use of this improved device, when a slat has its tenon broken and it is desired to repair the slat, the same is slightly pushed sidewise from the usual journal-recess 15 in the side frames of the shutter, whereupon the journal 10 of the attachment can be easily inserted into its journal-recess 15. The slat is then turned in a horizontal position or substantially so, and the flanges 11 can be se- 100

cured onto the ends of the slats by nails 16 or other suitable devices, whereby the slat is again in condition for use.

When an entire slat has fallen out, it is simply necessary to secure one of these improved attachments to one end thereof, insert its journal in the journal-recess of one side frame of the shutter, then insert the journal of another attachment in the journal-recess of the opposite side frame, and then secure it to the end of the slat in the usual way, whereby the necessity of taking the shutter apart to replace a slat is obviated.

By this improved shutter or blind slat attachment the unsightly appearance of a shutter or blind when one end of a slat or slats has become separated from its side frame and hangs to the shutter only by its other end or when the slat has fallen entirely out is obviated and the cost of repairing the shutters materially decreased. By having this tenon composed of sheet metal in the nature of flat wire the same can be stamped out at one operation, as hereinbefore stated, ready to be placed on the market, which is not the case with tenons made of sheet metal other than flat-wire sheet metal.

Having thus described my invention, I claim—

1. The flat-wire journal, its middle portion forming the end of a tenon, and the immediately-adjacent portions bent at right angles to the middle portion and parallel with each other and concaved on their inner sides, forming a tenon open at its sides throughout its length; and extensions diverging at right angles from the tenon thus formed and adapted for attachment to the end of the blind-slat.

2. The flat-wire journal, its middle portion forming the end of a tenon, and the immediately-adjacent portions bent at right angles to the middle portion and parallel with each other and concaved on their inner sides, forming a tenon open at its sides throughout its length; extensions diverging at right angles from the tenon thus formed, and each of said extensions having a bent projection at its end adapted for attachment to the end of the blind-slat.

EDWIN F. NEWELL.
